(57) **CLAIM**

The ornamental design for an audio and video accessory for an electronic device, as shown and described.

DESCRIPTION

FIG. 1 is a front view of the audio and video accessory for an electronic device according to a first embodiment of the present invention.

FIG. 2 is a rear view of the audio and video accessory for an electronic device of FIG. 1.

FIG. 3 is a left side view of the audio and video accessory for an electronic device of FIG. 1.

FIG. 4 is a right side view of the audio and video accessory for an electronic device of FIG. 1.

FIG. 5 is a bottom view of the audio and video accessory for an electronic device of FIG. 1.

FIG. 6 is a top view of the audio and video accessory for an electronic device of FIG. 1.

FIG. 7 is a front and left perspective view of the audio and video accessory for an electronic device according to the first embodiment of the present invention.

FIG. 8 is a front view of the audio and video accessory for an electronic device according to a second embodiment of the present invention.

FIG. 9 is a rear view of the audio and video accessory for an electronic device of FIG. 8.

FIG. 10 is a bottom view of the audio and video accessory for an electronic device of FIG. 8.

FIG. 11 is a top view of the audio and video accessory for an electronic device of FIG. 8.

FIG. 12 is a front and left perspective view of the audio and video accessory for an electronic device according to the second embodiment of the present invention.

FIG. 13 is a front view of the audio and video accessory for an electronic device according to a third embodiment of the present invention.

FIG. 14 is a rear view of the audio and video accessory for an electronic device of FIG. 13.

FIG. 15 is a left side view of the audio and video accessory for an electronic device of FIG. 13.

FIG. 16 is a right side view of the audio and video accessory for an electronic device of FIG. 13.

FIG. 17 is a bottom view of the audio and video accessory for an electronic device of FIG. 13.

FIG. 18 is a top view of the audio and video accessory for an electronic device of FIG. 13; and,

FIG. 19 is a front and left perspective view of the audio and video accessory for an electronic device according to the third embodiment of the present invention.

The broken line showing on FIGS. 1-19 is for illustrative purposes only and forms no part of the claimed design.
